(57) **CLAIM**

The ornamental design for a floor cleaning pad, as shown and described.

DESCRIPTION

FIG. 1 is a perspective view of a floor cleaning pad showing our new design;

FIG. 2 is a front end view thereof;

FIG. 3 is a top view thereof, the bottom view thereof being a mirror image of the top view shown;

FIG. 4 is a rear end view thereof; and,

FIG. 5 is a left side view thereof, the right side view thereof being a mirror image of the left side view shown.

The broken lines in the drawings are shown for illustrative purposes only and form no part of the claimed design. In addition, the surface shading illustrated in the drawings is provided merely to highlight the contour of design; it is not intended to be illustrative of texture or gloss.
